UNITED STATES PATENT OFFICE.

WILLIAM E. SHARPLES, OF FALL RIVER, MASSACHUSETTS.

AUTOMATIC THREAD-BOARD LIFTER.

SPECIFICATION forming part of Letters Patent No. 737,161, dated August 25, 1903.

Application filed February 14, 1903. Serial No. 143,430. (No model.)

To all whom it may concern:

Be it known that I, WILLIAM E. SHARPLES, a citizen of the United States, residing at Fall River, in the county of Bristol and State of Massachusetts, have invented certain new and useful Improvements in Automatic Thread-Board Lifters; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to thread-board lifters for ring-spinning frames—such, for instance, as the one shown in my United States Patent reissued August 11, 1896, No. 11,562.

The object of the invention is to provide improved means for raising the thread-board at any point when the ring-rail is near the top of the wind in order to relieve the yarn from all strain.

20 The invention consists in certain combinations and arrangements of parts, as hereinafter set forth, and particularly pointed out in the claims.

In the accompanying drawings, Figure 1 is a front elevation, partly in section, of a portion of a ring-spinning frame equipped with my invention. Fig. 2 is a side elevation, partly in section, of the same.

25 The roller-beam A, the thread-board B, hinged thereto at b, the guide-wire C on the thread-board, the spindle-rail D, the spindles E, mounted thereon, the bobbins F on said spindles, the ring-rail G, carrying the ring g and its traveler g', the lifting-rod H, attached to the ring-rail, the rock-shaft I, carrying an arm K, in the end of which is a slot k for the adjustment of the roller L, on which rests the foot H', secured to the lower end of the ring-rail-lifting rod H, and by means of which said rod is lifted and lowered, are all old and may 30 be of any desired construction.

Secured to the under side of the thread-board is a bent arm M, which passes downward and backward under the roller-beam A. A rearwardly-extending bracket N is bolted 35 to the roller-beam adjacent to said arm, and in its rear forked end is pivoted a cam-lever O, bearing on the arm M. The pivots of the

cam-lever can be adjusted along longitudinal slots n in the bracket to vary the point of contact with the arm M and thus alter the lift 40 of the thread-board. The cam can be turned down to depress the arm M and thus tilt up the thread-board, as shown in dotted lines in Fig. 2.

In order to actuate the cam-lever automatically, I provide on the rock-shaft I an arm P, by which is carried an adjustable holder for an upright rod Q, which passes through a fixed guide R and terminates below the tail of the cam-lever, with which it is not connected. The adjustable holder preferably consists of a clamp S, composed of two parts held together by a bolt s and clamping the arm P between them. One part of this clamp has a wrist-pin s' engaging the upper end of a pitman T, the lower end of which is provided with a sleeve t, through which the rod Q passes and in which it can be longitudinally adjusted by a set-screw t'.

The operation of my invention is as follows: 50 When the ring-rail is lifted by the rock-arm I, the arm P also raises the rod Q, and as the ring-rail nears the top of its wind the upper end of said rod strikes the tail of the cam-lever and carries it up, thus causing the cam 55 to force down the arm M and tilt up the thread-board. By means of the clamp the lift of the rod and of the thread-board can be regulated, and by means of the sleeve and set-screw the moment when the upper end of the rod will strike the cam-lever can be accurately timed.

Having thus described my invention, what I claim is—

1. In a ring-spinning frame, the combination with a hinged thread-board, of a rearwardly-extending arm secured thereto, a lever bearing upon said arm, a reciprocating rod adapted to actuate said lever, and a rock-arm on a rock-shaft of the machine for imparting motion to said rod. 90

2. In a ring-spinning frame, the combination with a hinged thread-board, of a rearwardly-extending arm secured thereto, a lever bearing upon said arm, a reciprocating rod having one end adjacent to but disconnected from said lever, and an arm on a rock-shaft of the machine for actuating said rod. 100

3. In a ring-spinning frame, the combina-

tion with a hinged thread-board, of a rearwardly-extending arm secured thereto, a stationary bracket adjacent to said arm, a cam-lever pivoted in said bracket, and bearing on 5 said arm, a reciprocating rod adapted to actuate said lever, and an arm on a rock-shaft of the machine for imparting motion to said rod.

4. In a ring-spinning frame, the combination with a hinged thread-board, of a rearwardly-extending arm secured thereto, a stationary forked and slotted bracket adjacent to said arm, a cam-lever having its pivots adjustably mounted in said slotted bracket, 10 said cam-lever bearing on the arm, a reciprocating rod for actuating said cam-lever, and means for actuating said rod.

5. In a ring-spinning frame, the combination with a hinged thread-board, of a rearwardly-extending arm secured thereto, a cam-lever bearing upon said arm, a reciprocating rod adapted to actuate said lever, and means 20 for actuating said rod, there being sufficient lost motion between the upper end of said rod and the lever to prevent their coming 25 into contact until the ring-rail of the machine is near the top of the wind.

In testimony whereof I affix my signature in presence of two witnesses.

WILLIAM E. SHARPLES.
